(57) **CLAIM**

The ornamental design for a mat connector, as shown and described.

DESCRIPTION

FIG. 1 is an end elevational view of the female portion of the mat connector.

FIG. 2 is an end elevational view of the male portion of the mat connector.

FIG. 3 is a top perspective view of the female portion of the mat connector which is broken in the centre indicating indefinite lengths.

FIG. 4 is a bottom perspective view of the female portion of the mat connector which is broken in the centre indicating indefinite length.

FIG. 5 is a top perspective view of the male portion of the mat connector which is broken in the centre indicating indefinite length.

FIG. 6 is a bottom perspective view of the male portion of the mat connector which is broken in the centre indicating indefinite length.

FIG. 7 is an assembled perspective view of the male and female portions of the mat connector. The female portion of the mat connector is shown positioned on top and is broken in the centre indicating indefinite length.

FIG. 8 is an assembled perspective view of the male and female portions of the mat connector. The female portion of the mat connector is shown positioned on bottom and is broken in the centre indicating indefinite length; and,

FIG. 9 is a cross-sectional view of the female portion and the male portion of the mat connector shown in the installed position together with a mat, in dashed lines.

The broken line showing is for illustrative purposes only and forms no part of the claimed design.

The elements of the claimed design have been shown separately for ease and clarity of illustration.
